UNITED STATES PATENT OFFICE.

EMANUEL D. WEBER, OF EASTON, PENNSYLVANIA.

COMBINED OUTLET-BOX AND LIGHT-FIXTURE.

No. 825,254.

Specification of Letters Patent.

Patented July 3, 1906.

Application filed May 23, 1905. Serial No. 261,839.

To all whom it may concern:

Be it known that I, EMANUEL DAVID WEBER, a citizen of the United States of America, residing at Easton, in the county of 5 Northampton and State of Pennsylvania, have invented a Combined Outlet-Box and Light-Fixture, of which the following is a specification.

This invention relates to improvements in 10 electric-light wiring, and particularly to electric-light wiring of that character known as "concealed porcelain knob and tube work," for combination gas and electric fixtures or straight electric fixtures.

One object of the invention is to provide a 15 safe, simple, and reliable insulating-receptacle located at the light-outlets or points in either ceilings or side walls where the wires terminate, the said receptacle to receive, retain, and protect the wires.

Another object is to provide a receptacle of 20 sufficient size to receive the current-carrying or supply wires, extending usually six to ten inches beyond the wall-line, also to receive all 25 necessary wires extending from the lighting-fixture, which wires are usually six or more inches in length and extending from the upper end of the fixture and are connected to the current-carrying or supply wire. These 30 wires are placed at the present time under the fixture-canopy—an uninsulated receptacle located at the top of the fixture. The canopy not being an insulated receptacle frequently has holes burned through it, caused 35 by grounded or short-circuited wires or static discharges occurring during electrical storms.

Another object is to provide an insulated 40 receptacle into which the wires (which are now left projecting beyond the ceiling or wall-line) may be placed, so that the wires will be securely protected from careless handling or unavoidable injury.

Another object is to provide an insulating-receptacle which will effectually prevent 45 grounding of the current and obviate all liability of induction or static discharges from the wires to the gas-supply pipe, the fixture-support, or the grounded or gas-pipe end of the insulating-joint.

Another object is to provide a construction 50 which will permit, if so desired, of the outlet of any gas which may escape from the gas-supply pipe at the outlet end, and thus obviate any possibility of a fire or explosion 55 from the ignition of the gas, and, finally, to generally simplify and improve the electric

wiring of fixture connections of this character and provide an outlet-box which conforms in all respects to the rules and regulations of the National Board of Fire Underwriters.

The preferred embodiment of the invention is illustrated in the accompanying drawings, in which—

Figure 1 is a central section through the 65 fixture as applied to a side wall or ceiling and connected with the gas-supply pipe. Fig. 2 is a similar view disclosing a modification.

The numeral 1 represents the side wall or ceiling of an apartment, and 2 a gas-supply 70 pipe which extends to the exterior thereof and is located, as usual, between the wall or ceiling and the adjacent wall or flooring. In accordance with my invention I provide an outlet-box 3, a gas-pipe insulator 6, and a sliding or threaded sleeve 14, all of which constitute the outlet-box complete and which are constructed of some insulating or non-conducting material. The outlet-box 3 is embedded in the wall or ceiling 1 and is open at its 75 outer end, which is flush with the wall or ceiling 1 and is closed at its inner end 4. The closed or inner end 4 of the outlet-box 3 is provided with a central opening 5 for the passage of the gas-supply pipe 2, the said opening 5 being made of sufficiently greater diameter than the gas-supply pipe 2 to receive an interposed insulating-tube 6, constituting a gas-pipe insulator which is frictionally engaged with the wall of the opening 5 or has a threaded 80 engagement therewith, as respectively shown in Figs. 1 and 2, and surrounds the gas-supply pipe 2 between the elbow 7 and the outer or fixture end 8 of the gas-supply pipe.

The sleeve 14 may have a threaded connection with the gas-pipe insulator 6 when the parts are horizontally disposed, as shown in Fig. 2, and a sliding connection when the parts are vertically disposed, as illustrated in Fig. 1. The sleeve 14 when made sliding and in final position rests at its lower end upon the insulation of the insulating-joint 9, thus closing the space at the connection of the insulating-joint 9 with the outlet end 8 of the gas-supply pipe 2, thereby preventing the supply-wires 17 or fixture-wires 19 from contacting the exposed end 8 of the gas-supply pipe 2 or the grounded end 11 of the insulating-joint 9, thus lessening the liability of the supply-wires 17 or fixture-wires 19 becoming defective by grounding or static discharges during electrical storms and preventing electro-

lytic action at this point. The insulating-joint or coupling member 9 has a threaded engagement at 11 and 12, respectively, with the pipe 2 and fixture-stem 10.

5 The sleeve 14 when made sliding on the gas-pipe insulator 6 will allow of the outlet of any gas that may escape at the connection of the insulating-joint 9 to the gas-pipe outlet end 8, as the gas may pass between the gas-pipe insulator 6 and the gas-supply pipe 2 into space back of the plastering or wall-line 1 or flow between the gas-pipe insulator 6 and the sliding sleeve 14 into the outlet-box 3, and thence through the insulating-tubes 16 into the space back of the plastering or wall-line.

The tubes 16 are fitted in the openings 15 for the supply-wires 17. These openings may be made either in the rear end 4 of the outlet-box 3, as shown, or in the sides of the outlet-box 3. These openings are made of sufficient size to allow of the insertion of flexible tubes or bushings 16 of proper diameter for the passage of the supply-wires 17, which 25 extend therethrough into the outlet-box 3. This construction provides an effective insulating connection which conforms with the current rules of the National Board of Fire Underwriters.

30 The supply-wires 17 usually extend beyond the ceiling or wall-line 1 from six to ten inches. One of the benefits of the outlet-box 3 is to form a receptacle into which the supply-wires may be tucked out of the way of injury during the lathing, plastering, and finishing processes of building construction.

When buildings are completed and fixtures hung, the ends of the fixture-wires 19, which are usually from six to ten inches long and end 40 after the fixture-stem 10 through an opening or openings 10' therein, are connected at their ends with the ends of the supply-wires 17, and the wires when connected can be placed in the outlet-box 3, where there will be ample room and where they will be protected and completely insulated from contact with any part of the gas-supply pipe 2 or the grounded end 11 of the insulating-joint 9. The outlet-box 3 in practice will be made sufficiently large to receive and retain the spare or slack portions of wires 17 and 19 without crowding. By the use of this outlet-box 3 the objectionable practice of confining wires under the fixture-canopy 20 is obviated, and 55 the liability of fires and other troubles and annoyances caused by the use of an uninsulated metallic canopy lessened.

The pipe 2, forming the fixture-support, is termed a "gas" or "gas-supply" pipe, as its ordinary function is to support and supply 60 gas to a gas-burner fixture, one object of the invention being, as will be readily understood, to utilize the ordinary gas-supply pipe projecting through the wall of a room as a support for an electric-light fixture, so as to

70 avoid the expense of installing independent fixture-supports in buildings supplied with the usual gas-light equipment. In many buildings independent gas and electric light fixtures are used in different rooms, and in such cases the gas cannot be cut off from the pipes supporting the electric-light fixtures without also cutting off its flow to the other pipes to which the gas-burners are attached. Hence the insulating-joint 9 is employed to 75 close each pipe to which an electric-light fixture is attached and to support such fixture therefrom. The purpose of the other parts of the invention will be obvious from the foregoing description and explanation. 80

Of course any other suitable fixture-support may be employed in place of the pipe 2—as, for instance, when electric-lighting fixtures are alone used or are intended to be supported independent of the pipes of a gas-service system in a building supplied with such system. The box 3 may be used in either case as a receptacle for the spare or slack portions of the wires to obviate the objectionable practice of confining the same 90 under the fixture-canopy 20.

Having thus described the invention, what is claimed as new is—

1. In an electric-light fixture, the combination of a gas-pipe, an insulating outlet-box 95 surrounding the pipe, an insulating-sleeve surrounding the inclosed portion of the pipe, and a second insulating-sleeve engaging the first-named sleeve and inclosing the projecting portion of the pipe. 100

2. In an electric-light fixture, the combination of a gas-pipe, an insulating outlet-box surrounding the pipe, said box being provided with openings for the passage of conductors, an insulating-sleeve surrounding the 105 inclosed portion of the pipe, and a second insulating-sleeve inclosing the projecting portion of the pipe, said sleeves being arranged to form a vent for the escape of gas leaking from the pipe. 110

3. In an electric-light fixture, the combination of an outlet-box provided with insulated passages for lead-wires, a pipe projecting through said box, an insulating-sleeve supported by the box and surrounding the 115 inclosed portion of the pipe, and a second sleeve adjustably mounted on the first-named sleeve and inclosing the projecting portion of the pipe. 120

4. In an electric-light fixture, the combination of an outlet-box, a pipe projecting through said box, an insulating-sleeve supported by the box and surrounding the 125 inclosed portion of the pipe, and a second sleeve slidably engaging the first-named sleeve and inclosing the projecting portion of the pipe. 130

5. In an electric-light fixture, the combination of an insulating outlet-box having openings, a pipe projecting through one of 135 said openings and extending through the box,

insulating-tubes for the lead-wires mounted in the other openings, an insulating-sleeve mounted in the opening through which the pipe projects and surrounding the inclosed 5 portion of the pipe and a portion of the pipe beyond the wall of the box in which the opening is formed, and a second insulating-sleeve adjustably engaging the first-named sleeve and surrounding the outer extremity of 10 the pipe.

6. In an electric-light fixture, the combination with a wall, of an outlet-box embedded therein and having an open side flush with the wall-surface, a gas-pipe extending 15 through the box beyond said surface, a fixture-stem coupled to the outer end of the pipe, a canopy inclosing said stem and outer end of the pipe, wires extending through said stem and also through the outlet-box, the 20 latter being arranged to form a pocket or chamber for the storage of slack portions of the wire, an insulating-sleeve supported by

the box and surrounding the inclosed portion of the pipe, and a second insulating-sleeve adjustably engaging the first-named sleeve 25 and surrounding the projecting portion of the pipe about the joint.

7. In an electric-light fixture, the combination with a gas-supply pipe, of a fixture-stem connected therewith and insulated 30 therefrom, an insulating outlet-box embedded in the wall and surrounding and insulated from the pipe, a canopy and conducting-wires extending into the box and leading to the stem, said box being arranged to form a 35 protecting chamber or receptacle for spare or slack portions of said wires, substantially as described.

In testimony whereof I affix my signature in presence of two witnesses.

EMANUEL D. WEBER.
